JOHN WEBSTER COCHRAN, OF NEW YORK, N. Y.

Letters Patent No. 75,625, dated March 17, 1868.

IMPROVEMENT IN FIXED-AMMUNITION HOLDERS FOR CARTRIDGE-BOXES.

The Schedule referred to in these Letters Patent and making part of the same.

TO ALL WHOM IT MAY CONCERN:

Be it known that I, JOHN WEBSTER COCHRAN, of the city, county, and State of New York, have invented a new and useful Improvement in Holders for Cartridge-Boxes; and I do hereby declare that the following is a full, clear, and exact description of the same, reference being had to the accompanying drawings, making a portion of this specification, in which—

Figure 1 is a front view of a holder made according to my invention.

Figure 2 is a side or edge view of the same.

Figure 3 is a longitudinal section of the same.

Similar letters of reference indicate corresponding parts in all the figures.

This invention relates to that class of holders for cartridge-boxes designed for carrying metallic cartridges, and constructed to hold the rims or flanges of the cartridges, to retain the same in position, and which, as heretofore made, have consisted of metallic plates, having their lateral edges turned over to form longitudinal lips, behind which the flanges of the cartridges are passed when the latter are attached to the holders. This variety of holder has been found defective, inasmuch as the flanges of the several cartridges in the holder rest one upon another, and are thus very liable to be bruised or bent out of shape, in the vicissitudes to which the cartridges are exposed when carried by the soldier, and, furthermore, are liable to become loosened from the holder, for the reason that only the two opposite sides or edges of the flanges are acted upon or held by the hereinbefore-mentioned lips.

The object of this invention is to obviate these defects, and also to enable the cartridges to be removed from the holder, when required for use, with greater facility than has hitherto been practicable.

The invention consists in a plate, constructed with a series of separately-grooved sockets, which receive the flanged portions of the cartridges, in such manner that, each cartridge being held separately and by the greater portion of its flange, the objects mentioned are effectually secured.

To enable others to understand the nature and construction of my invention, I will proceed to describe it with reference to the drawings.

A represents the back of the cartridge-box, within which the holder is designed to be employed, and B indicates the holder itself, which is affixed to the said back in any suitable manner. The holder B is formed of a metallic plate, the front side of which is formed with a series of parts, *a*, situated one above another, and the surfaces of which are inclined in planes, nearly or quite parallel with each other, as shown in figs. 2 and 3. The central and front portion of each of these parts, *a*, is recessed or hollowed, as shown more fully at *a**, in fig. 1. The lower portion of such recess or hollow is of semicircular form; while the sides thereof are vertical, and the top of such recess is wholly open, as represented in fig. 1, the aforesaid recess or hollow being furthermore of a width equal to or only very slightly exceeding the diameter of the cartridge immediately forward of the flange thereof. Provided in the internal edges of each of the parts *a*, thus recessed or hollowed, is a groove, *a'*, of a depth equal to or slightly exceeding the width of the rim or flange of the cartridge to be held therein, as presently herein explained, and of a width corresponding to the thickness of such flange.

The parts *a* thus formed, with the recesses *a** and grooves *a'*, constitute sockets, each of which receives the base of a cartridge, as follows: The cartridge, indicated at C, in figs. 2 and 3, is grasped with the fingers, and its flange or rim *b* is thrust or passed downward into the groove *a'*, the body or main portion of the cartridge projecting forward through the recess *a**. The cartridge being pushed downward, until its body rests upon or is supported at the semicircular bottom of the recess *a**, as represented in fig. 3, the larger portion of the flange or rim is situated or fitted within the groove *a'*, as shown more fully in fig. 1, so that the aforesaid flange, being thus fixed or confined, the cartridge is supported in the nearly horizontal position indicated in figs. 2 and 3.

The sockets *a*, hereinbefore fully described, being arranged at a suitable distance apart, the cartridges are kept separated from each other, thus obviating all liability of injury thereto, which would otherwise be likely to occur, from their forcible contact or jamming against each other. Furthermore, inasmuch as the open top of each socket is situated forward of the lower part of the socket above it, owing to the inclined position, hereinbefore described, of the parts *b*, constituting the said sockets, it follows that in order to remove the cartridges from the holder, commencing at the top, it is only necessary to move the cartridge upward a distance equal to

the internal length of the socket, in order to bring the flange of the cartridge from such socket, and thus completely detach the cartridge from the holder. It is intended that one or more of the holders be employed in a single cartridge-box, according to the number of vertical series of sockets preferred therein, or, if desired, any requisite number of such series of sockets may be formed upon a single plate or holder. What I claim as my invention, and desire to secure by Letters Patent, is— The cartridge-holder, constructed with the series of separately-grooved sockets *a*, formed and arranged in relation with each other substantially as and for the purposes specified.

J. W. COCHRAN.
